UNITED STATES PATENT OFFICE.

JOHN D. BICKERSTAFF, OF HOBART, OKLAHOMA.

BALING-PRESS.

1,241,491.

Specification of Letters Patent.

Patented Oct. 2, 1917.

Application filed November 3, 1916. Serial No. 129,359.

To all whom it may concern:

Be it known that I, JOHN D. BICKERSTAFF, a citizen of the United States, residing at Hobart, in the county of Kiowa and 5 State of Oklahoma, have invented certain new and useful Improvements in Baling-Presses, of which the following is a specification.

My invention relates to an attachment, 10 for use in connection with baling presses, having movable or swinging sides, to normally retain the sides in the closed or inner position, and to release the same, when it is desired to move them to the open or outer 15 position.

An important object of the invention is to provide means of the above mentioned character, which is simple in construction, inexpensive to manufacture, strong, durable, and convenient in use.

Other objects and advantages of the invention will be apparent during the course of the following description.

In the accompanying drawings forming 25 a part of this specification and in which like numerals are employed to designate like parts throughout the same,

Figure 1 is a side elevation of a press having my attachment applied thereto,

Fig. 2 is a plan view of the same,

Fig. 3 is an end elevation of the same,

Fig. 4 is a transverse sectional view taken on line 4—4 of Fig. 1, and,

Fig. 5 is a detail section taken through 35 one of the operating cylinders and associated elements of the attachment.

In the drawings, wherein for the purpose of illustration is shown a preferred embodiment of my invention, the numeral 10 designates longitudinal beams of the top-member 40 of the press. Secured to the lower surface of these beams 10 are spaced transverse strips 11, as shown. Rigidly connected with the ends of the beam 10 are vertical bars or rods 12, extending downwardly for 45 rigid connection with transverse bottom bars or members 12', as shown.

Strips 13 are arranged inwardly of the bars 11, between beams 10 and 12', and 50 serve to close the ends of the press.

The numeral 14 designates the sides of the press, each of which comprises an upper horizontal beam 15, preferably arranged upon the outer sides of spaced strips or 55 slats 16, and rigidly secured thereto. The strips 16 are rigidly attached at their lower

ends to a horizontal beam 17, which is arranged upon the outer sides thereof. The beams 17 are provided at their ends with reduced cylindrical extensions or trunnions 60 18, adapted to be pivotally mounted within cylindrical openings 19, formed in the transverse beams 12'. The openings 19 afford means whereby the pivot points of the sides 14 may be adjusted inwardly or outwardly with respect to the beams 12', the trunnions 18 being removed from the openings 19 by prying the beams 12' apart.

As more clearly shown in Fig. 4, the numeral 20 designates the bottom-plunger 70 of the press, which is vertically movable.

My attachment comprises cylinders 21 arranged at opposite ends of the press near and beneath the beams 10. As shown in Fig. 5, each cylinder 21 has its ends closed 75 by caps 22, preferably having screw-threaded engagement therewith. Mounted to reciprocate within the cylinder 21 are pistons 23, having connection with piston rods 24, operating through stuffing boxes 25. The 80 piston rods 24 have their ends up-turned or hooked, as shown at 26, to engage within rings 27, carried by eye-bolts 28, which pass through the ends of the beams 10 and are rigidly connected therewith.

As clearly shown in Fig. 5, pipes 29 lead into the caps 22, and hence into the opposite ends of the cylinder 21, and these pipes connect with a pipe 30, having connection with a pipe 31. As more clearly shown in Fig. 90 1, the pipe 31 has a T-coupling 32 connected therein, which has connection with a pressure supply pipe 33, having a cut off valve 34 connected therein. The pressure supply pipe 31 has an exhaust pipe 35 connected 95 therein, which has a cut off valve 36 connected therein, as shown.

As more clearly shown in Figs. 1, 3 and 4, the beams 10 are provided upon their lower edges with openings or notches 37, which receive the transverse pipes 30, therein. The cylinders 21 and associated elements are supported by transverse bars 38, which engage with the upper sides of the beams 10 and have openings 39 for the passage of the ends 100 of the pipe 31, such pipe being held therein by means of clamping bolts 40 or the like.

The operation of the apparatus is as follows:

The sides 14 may be swung to a more or less open position, as indicated in dotted lines, in Fig. 3, and the material to be pressed

into bales, such as paper, fed therebetween upon the bottom 20. The sides 14 are then swung inwardly by hand and the rings 27 engaged upon the hooked ends 26 of the piston rods 24, such piston rods being in the outer position. The exhaust valve 36 is closed and the supply valve 34 is opened whereby pressure is simultaneously supplied to the opposite ends of the two cylinders.

10 This application of pressure within the cylinder causes the pistons 23 to move inwardly, drawing the piston rods 24 inwardly. These movements of the piston rods swing the sides 14 to the inner position and the pressure is retained in the cylinders, during the pressing operation, whereby the sides are locked in the inner position. The bottom-plunger 20 is moved upwardly to press the material into the bale. When the material

20 is pressed into the bale the usual binding wires or strips may be passed about the bale. The pressure supply valve 34 is now closed and the exhaust valve 36 is opened whereby the pressure exhausts from the cylinders 21 to the atmosphere or in supply tank. The pistons 23 are now free to move outwardly, and the rings 27 may disengage the rods 24. The bottom plunger 20 is lowered, and the bale may be pushed out of the press through either open side thereof.

30

It is obvious that my attachment may be used in connection with various presses, and the use in connection with the press shown is for the purpose of illustration, and the invention is in no sense restricted to such application.

It is to be understood that the form of my invention herewith shown and described is to be taken as a preferred example of the same, and that various changes in the shape, size, and arrangement of parts may be re-

sorted to without departing from the spirit of the invention or the scope of the subjoined claims.

Having thus described my invention, I claim:

1. The combination of a press comprising upper longitudinal stationary beams and vertically swinging side members, of cylinders arranged near the ends of the upper beams and extending transversely thereof and connected thereto for support, a conduit provided at its ends with approximately U-shaped branches having their ends leading into the opposite ends of the cylinder, means for supplying pressure into the conduits and exhausting pressure therefrom, pistons mounted to slide within the cylinders, and means for detachably connecting the pistons with the side members.

2. The combination with a press comprising upper longitudinal beams and vertically swinging side members; of cylinders arranged near and below the ends of the upper beams, a conduit provided at its ends with approximately U-shaped branches having transverse portions to contact with the lower portions of the upper beams and their ends leading into the opposite ends of the cylinders, means for suspending the conduit from the upper longitudinal beams, means for supplying pressure into the conduit and exhausting pressure therefrom, pistons mounted to slide within the cylinders, and means for detachably connecting the pistons with the side members.

In testimony whereof I affix my signature in presence of two witnesses.

JOHN D. BICKERSTAFF.

Witnesses:

J. R. HUNTER,
J. T. BAILEY.
